UNITED STATES PATENT OFFICE.

ALFONZO C. VAN SLYKE, OF CRESO, IOWA.

SWEEP-OPERATED WINDLASS.

No. 902,701.

Specification of Letters Patent.

Patented Nov. 3, 1908.

Application filed May 14, 1908. Serial No. 432,957.

To all whom it may concern:

Be it known that I, ALFONZO C. VAN SLYKE, citizen of the United States, residing at Cresco, in the county of Howard and State of Iowa, have invented new and useful Improvements in Sweep-Operated Windlasses, of which the following is a specification.

My invention pertains to sweep-operated windlasses such as are designed more particularly for use in pulling stumps; and it has for its object to provide a strong, efficient and easily controlled sweep-operated windlass, of simple and inexpensive construction, and one in which adequate provision is made for keeping a cable in order and preventing frictional wear thereof.

The novelty, utility and practical advantages of the invention will be fully understood from the following description and claims when the same are read in connection with the drawings, accompanying and forming part of this specification, in which:

Figure 1 is a side elevation of the windlass constituting the best practical embodiment of my invention of which I am aware. Fig. 2 is a plan view of the windlass. Fig. 3 is a detail view, partly in elevation and partly in vertical section, illustrating my novel means for putting the drum of the windlass in and out of gear. Fig. 4 is a horizontal section taken in the plane indicated by the line 4-4 of Fig. 1, looking downward, and with a portion of the frame of the windlass broken away. Fig. 5 is a broken elevation, partly in section, showing the spindle of the windlass and certain appurtenances thereof. Fig. 6 is a plan view of the vertically adjustable clutch member comprised in my improvements, and: Fig. 7 is an inverted plan view of the spindle.

Similar letters designate corresponding parts in all of the views of the drawings, referring to which:

A is the bottom plate of the windlass, which is bolted or otherwise secured on transverse timbers *a* fixed with respect to longitudinally disposed timbers *b*, and is provided with a central raised portion *c*, and a stud *d*, see dotted lines in Fig. 1, rising from the center of the said raised portion *c*. The timbers *a* and *b* form a rectangular base frame, and I prefer to strengthen the said base frame by using metallic bars *e* which extend between and are connected to

the transverse timbers *a* and are arranged above the longitudinally disposed timbers *b*, as best shown in Fig. 2.

B is a top casting which is arranged a suitable distance above the bottom plate A 60 and is provided with a central, circular bearing *e'* for the upper portion of the drum, presently described.

C is a front upright, preferably of metal, having angular end portions *f* arranged parallel with and connected to the base plate A 65 and the top casting B.

D is an upright roller interposed between and journaled in lateral lugs *f'* on the said portions *f* and having for its office to prevent frictional wear of a cable incidental to the passage of the same to and from the drum, and E is an open frame bolted or otherwise fixed to the opposite ends of the bottom plate A and top casting B, with 70 reference to the upright C. The said open frame E, which is preferably of metal, is provided in its outer portion with an opening *g*, the outer wall of which is notched at intervals of its height, as indicated by *h*, 80 for the connection of an anchor cable (not shown); the plurality of notches *h* being provided in order that the anchor cable may be connected at various heights to the frame E in order to meet different conditions. 85

F is the drum of the apparatus which is mounted on the raised portion *c* of the bottom plate A, and has a reduced upper portion *i*, see Figs. 1 and 3, journaled in the circular bearing *e'* of the top casting B, 90 whereby it will be manifest that the drum is adapted to be freely rotated about its axis. Extending vertically through the drum F is a spindle G, the lower end of which is disposed over the stud *d* on the bottom plate A so as to enable the spindle to hold the lower end of the drum against casual movement or displacement. The drum is loose on the spindle and hence is enabled to freely turn in either direction 95 about the same.

As best shown in Figs. 1 to 3, the drum F is provided adjacent to its upper end with a circumferential series of ratchet teeth *j*, and is also provided with a circular series 105 of clutch teeth *k*, and a hand ring *l*; the clutch teeth *k* being arranged on the upper end of the reduced portion *i*, and the hand ring *l* being arranged below the ratchet teeth *j* and being designed to enable an attendant 110

to turn the drum in either direction by hand. I also prefer to provide the drum with the usual holes *m* for the connection of a cable.

The drum *F* is designed to be sweep-operated in the direction indicated by arrow in Fig. 2, and with a view of preventing retrograde movement of the drum I provide the dog *n*, pivoted on a stud *p* depending from the top casting *B*, and arranged to engage the ratchet teeth *j* on the drum. The said dog *n* is normally maintained in the position illustrated by a coiled spring *r* connected to the front upright *C*, and in order that the dog may be disengaged from and held out of engagement with the teeth *j*, as when it is desired to turn the drum in the direction opposite to that indicated by arrow, I provide the cam lever *s* which is fulcrumed on a stud *t* depending from the top casting *B* and is arranged in engagement with the outer arm of the dog, after the manner best shown by dotted lines in Fig. 2.

H and *I* are lower and upper brackets fixed to the inner upright bar of the open frame *E* and curved in conformity to the drum, Fig. 4, and having apertured lugs *u*.

J and *K* are lower and upper brackets fixed to the front upright *C* and arranged at the opposite side of the drum, with reference to the brackets *H* and *I*, and curved in conformity to the drum and having apertured lugs *v*.

L is an upright roller arranged at one side of the drum and *M* is an upright roller arranged at the opposite side of the drum. These rollers *L* and *M* have for their office to bear against the superposed coils of a cable on the drum and retain the same in proper order, and they may be spirally grooved as shown, or else may be provided with plain peripheries in the discretion of the manufacturer of the windlass. The roller *L* is carried by a horizontally swinging frame *N*, pivoted at *w* to the brackets *H* and *I*, and provided with lugs *x* in which and the lugs *u* of the brackets are arranged rods *y* which are surrounded by coiled springs *z*, designed by virtue of their interposition between the lugs *u* and the lugs *x* to yieldingly press the frame *N* and the roller *L* inward and hold the latter against a cable and to its work. The roller *M* is carried by a similar frame *N* which is pivoted at *w* to the brackets *J* and *K* and is provided with apertured lugs *x* through which and the lugs *v* of the brackets extend rods *y* on which are mounted coiled springs *z*, designed because of their interposition between the lugs *v* and *x* to yieldingly press the frame *N* and the roller *M* inwardly. It will be readily understood in this connection that by virtue of the rollers *L* and *M* bearing against the cable at opposite points, with reference to the drum, and the roller *D* be-

ing located at a point intermediate the rollers *L* and *M*, the cable will be maintained under all conditions in superposed coils on the drum and will not be subjected to frictional wear during its passage to and from the drum.

P is a longitudinal central runner fixed to the under sides of the timbers *a* and the under side of the frame *E* and having beveled ends, and *R*, Fig. 1, is one of two comparatively short runners, fixed to the under sides of the timbers *a* and *b*, and disposed at opposite sides of the runner *P*. The runners, as their name implies, are designed to facilitate movement of the apparatus over the ground.

S is a sweep plate disposed above the top casting *B*, as best shown in Fig. 9, and *T* is a sweep fixed to one end of the plate *S* and extending at a right angle therefrom. Between the opposite end of the plate *S* and the sweep *T* is arranged a brace rod *U* which serves to materially strengthen the connection between the two parts. The sweep plate *S* is provided, as shown in Fig. 9, with an opening *a'* which is shaped in conformity to and is designed to snugly receive the angular portion *b'* of the spindle *G*, whereby it will be seen that when the plate *S* is turned the spindle *G* will turn therewith. The said spindle *G* is provided at its upper end with a flange *c'* bolted to the upper side of the sweep plate, and serving to prevent vertical movement of either the spindle or the sweep plate with respect to each other. The sweep plate *S* is provided at opposite sides of the flange *c'*, Fig. 2, with vertically disposed openings *d'*, through which extend vertically movable links *f'* which are connected at their lower ends to the vertically movable clutch member *W*. The said vertically movable clutch member *W* is provided with an angular aperture *g'* which snugly receives the angular portion *b'* of the spindle *G*, and hence it will be seen that the member *W* is adapted to be moved vertically on and with respect to the spindle *G*, and yet will always derive circular motion from and turn with the said spindle which, in turn, derives rotary motion from the sweep plate *S* in the manner before described. On its lower edge the clutch member *W* is provided with teeth *h'* corresponding to and adapted to engage the teeth *h* of the drum, and consequently it will be seen that when the clutch member *W* is raised, as shown by dotted lines in Fig. 3, the drum *F* is left free to be turned in either direction independent of the clutch member, and it will also be seen that when the said clutch member is lowered to put its teeth *h'* in engagement with the teeth *h* of the drum, the drum will be caused to turn in the direction indicated by the arrow in Fig. 2, with the clutch member *W*, the spin-

ning located at a point intermediate the rollers *L* and *M*, the cable will be maintained under all conditions in superposed coils on the drum and will not be subjected to frictional wear during its passage to and from the drum.

P is a longitudinal central runner fixed to the under sides of the timbers *a* and the under side of the frame *E* and having beveled ends, and *R*, Fig. 1, is one of two comparatively short runners, fixed to the under sides of the timbers *a* and *b*, and disposed at opposite sides of the runner *P*. The runners, as their name implies, are designed to facilitate movement of the apparatus over the ground.

S is a sweep plate disposed above the top casting *B*, as best shown in Fig. 9, and *T* is a sweep fixed to one end of the plate *S* and extending at a right angle therefrom. Between the opposite end of the plate *S* and the sweep *T* is arranged a brace rod *U* which serves to materially strengthen the connection between the two parts. The sweep plate *S* is provided, as shown in Fig. 9, with an opening *a'* which is shaped in conformity to and is designed to snugly receive the angular portion *b'* of the spindle *G*, whereby it will be seen that when the plate *S* is turned the spindle *G* will turn therewith. The said spindle *G* is provided at its upper end with a flange *c'* bolted to the upper side of the sweep plate, and serving to prevent vertical movement of either the spindle or the sweep plate with respect to each other. The sweep plate *S* is provided at opposite sides of the flange *c'*, Fig. 2, with vertically disposed openings *d'*, through which extend vertically movable links *f'* which are connected at their lower ends to the vertically movable clutch member *W*. The said vertically movable clutch member *W* is provided with an angular aperture *g'* which snugly receives the angular portion *b'* of the spindle *G*, and hence it will be seen that the member *W* is adapted to be moved vertically on and with respect to the spindle *G*, and yet will always derive circular motion from and turn with the said spindle which, in turn, derives rotary motion from the sweep plate *S* in the manner before described. On its lower edge the clutch member *W* is provided with teeth *h'* corresponding to and adapted to engage the teeth *h* of the drum, and consequently it will be seen that when the clutch member *W* is raised, as shown by dotted lines in Fig. 3, the drum *F* is left free to be turned in either direction independent of the clutch member, and it will also be seen that when the said clutch member is lowered to put its teeth *h'* in engagement with the teeth *h* of the drum, the drum will be caused to turn in the direction indicated by the arrow in Fig. 2, with the clutch member *W*, the spin-

ning located at a point intermediate the rollers *L* and *M*, the cable will be maintained under all conditions in superposed coils on the drum and will not be subjected to frictional wear during its passage to and from the drum.

dle G, the sweep plate S and the sweep T, it being understood of course that the sweep is then being moved in the direction indicated by arrow by a team of horses hitched 5 in the conventional or any other suitable manner thereto.

For the purpose of raising and lowering the clutch member W and adjustably fixing the same in different positions, I provide the 0 mechanism best shown in Figs. 1, 3 and 5, which mechanism comprises a cross-bar m' fixed on the upper end of the spindle G, vertically swinging levers p' fulcrumed on the ends of the cross-bar m' and having their 5 lower arms pivotally connected to the links f' , a keeper r' fixed to and rising from the sweep T and having a transverse bolt s' , and a handle bar t' pivotally connected to the upper arms of the levers p' and having 0 notches u' at intervals of its length designed to be placed in engagement with the said transverse bolt s' of the keeper. When the handle bar t' is manipulated to rock the upper arms of the levers p' toward the 5 keeper r' and thereby raise the links f' and the clutch member W, and the forward notch u' of the handle bar is placed in engagement with the keeper bolt s' , it will be seen that the clutch member W will be secured in its raised position, while when the handle bar t' is manipulated to swing the upper arms of the levers p' in the opposite direction and thereby lower the links f' and the clutch member W, and the rear notch u' 5 of the handle bar is placed in engagement with the keeper bolt s' , it will be understood that the clutch member W will be secured in its lower working position—*i. e.*, in engagement with the teeth h of the drum F.

0 It will be gathered from the foregoing that the handle bar t' may be operated with facility by an attendant walking in rear of the sweep T and driving the animals hitched to the sweep, and consequently said attendant may, when occasion demands, put the drum F out of operation without stopping the team.

Having described my invention, what I claim and desire to secure by Letters-Pat-0 ent, is:

1. In a sweep-operated windlass, the combination of a frame, a spindle mounted in the frame and having an upper portion of angular form in cross-section, a drum 5 mounted in the frame and loosely surrounding the spindle and having clutch teeth at its upper end, a vertically adjustable clutch member having teeth to engage those of the drum and also having an angular aperture receiving the angular portion of the spindle, a sweep plate supported on the frame and having an angular aperture receiving the angular portion of the spindle and also having vertically disposed openings at opposite 5 sides of the spindle, a sweep fixed with re-

spect to the sweep plate, a cross-bar fixed on the spindle, above the sweep plate, links movable vertically through the said openings in the sweep plate and pivotally connected to the said clutch member, and a lever 70 fulcrumed at an intermediate point of its length on the said cross-bar and connected below its center of movement to the said links.

2. In a sweep-operated windlass, the combination of a frame, a spindle mounted in the frame and having an upper portion of angular form in cross-section, a drum mounted in the frame and loosely surrounding the spindle and having clutch teeth at 75 its upper end, a vertically adjustable clutch member having teeth to engage those of the drum and also having an angular aperture receiving the angular portion of the spindle, a sweep plate supported on the frame and 80 having an angular aperture receiving the angular portion of the spindle and also having vertically disposed openings at opposite sides of the spindle, a sweep fixed with respect to the sweep plate, a cross-bar fixed on 85 the spindle, above the sweep plate, links movable vertically through the said openings in the sweep plate and pivotally connected to the said clutch member, a lever fulcrumed at an intermediate point of its 90 length on the said cross-bar and connected below its center of movement with the said links, a keeper on the sweep at a point remote from the sweep plate, and a handle bar 95 pivoted to the upper arm of the lever and having notches at different points in its 100 length arranged to be engaged with and disengaged from the said keeper.

3. In a sweep-operated windlass, the combination of a frame comprising a bottom plate and a top casting having a central bearing, a spindle mounted on the bottom plate of the frame and extending through the said bearing of the top casting and having a flange on its upper portion and a portion, of angular form in cross-section, below said flange, a drum mounted on the bottom plate and in the bearing of the top casting and loosely surrounding the spindle and having clutch teeth at its upper end, a vertically adjustable clutch member having teeth to engage those of the drum and also having an angular aperture receiving the angular portion of the spindle, a sweep plate supported on the top casting and below the 110 flange on the spindle and having an angular aperture receiving the angular portion of the spindle and also having vertically disposed openings at opposite sides of the spindle, means connecting the flange on the 115 spindle to the sweep plate, a sweep fixed to and extending at a right angle from one end of the sweep plate, a cross-bar fixed on the upper end of the spindle and disposed above the sweep plate, links movable vertically 120

125

130

- through the said openings in the sweep plate and pivotally connected to the said clutch member, a lever having portions fulcrumed at an intermediate point on the said cross-bar and connected below said cross-bar to the said links, a handle bar connected to the lever above the cross-bar, and coöperating means on the sweep and the handle bar for adjustably fixing the latter in position.
- 10 4. The combination in a windlass, of a frame, a drum mounted to turn therein, brackets fixed to the frame and resting at opposite sides of the drum, horizontally swinging frames pivoted to the said brackets at intermediate points in the length of the latter, upright rollers mounted in the outer portions of the said horizontally swinging frames and arranged to bear against a cable on the drum, springs interposed and supported between the brackets and the horizontally swinging frames at intermediate points in the length of the latter for yieldingly pressing the swinging frames and the rollers inwardly.
- 15 5. The combination in a windlass, of a frame, a drum mounted to turn therein, brackets fixed to the frame, at opposite sides of the drum and extending from the frame in opposite directions alongside of and adjacent to the drum and having apertured lugs, horizontally swinging frames pivoted to the brackets and having apertured lugs opposed to those of the brackets, upright rollers mounted in said frames and arranged to
- 20 bear against a cable on the drum, bolts extending through and supported by the opposed lugs of the brackets and frames, and coiled springs mounted on said bolts and interposed between the brackets and frames.
- 25 6. The combination in a windlass, of a drum mounted to turn therein, brackets fixed

to the frame and resting at opposite sides of the drum, horizontally swinging frames pivoted to the said brackets at intermediate points in the length of the latter, upright rollers mounted in the outer portions of the said horizontally swinging frames and arranged to bear against a cable on the drum, springs interposed and supported between the brackets and the horizontally swinging frames at intermediate points in the length of the latter for yieldingly pressing the swinging frames and the rollers inwardly, and an upright roller journaled in stationary bearings in the frame and arranged intermediate the movable rollers to prevent frictional wear of the cable incidental to passage thereof to and from the drum.

7. The combination in a windlass, of transversely disposed base timbers, a bottom plate fixed thereon, a top casting, a drum bearing on the bottom plate and in the top casting, a front upright interposed between and connected to the bottom plate and the top casting, an open frame interposed between and connected to the bottom plate and top casting and extending rearward therefrom and at an angle to the base timbers, a longitudinal-central runner arranged below and fixed to the base timbers and extending throughout the length of and fixed to the said open frame, and runners arranged parallel to the longitudinal-central runner and fixed below the base timbers at opposite sides of said longitudinal-central runner.

In testimony whereof I have hereunto set my hand in presence of two subscribing witnesses.
